(57) **CLAIM**

The ornamental design for a cockpit display screen portion with a transitional graphical user interface, as shown and described.

DESCRIPTION

FIG. 1 is a front view of a cockpit display screen portion showing an image in a transitional sequence of the claimed design;

FIG. 2 is a front view of a cockpit display screen portion showing an image in a transitional sequence of the claimed design;

FIG. 3 is a front view of a cockpit display screen portion showing an image in a transitional sequence of the claimed design;

FIG. 4 is a front view of a cockpit display screen portion showing an image in a transitional sequence of the claimed design;

FIG. 5 is a front view of a cockpit display screen portion showing an image in a transitional sequence of the claimed design;

FIG. 6 is a front view of a cockpit display screen portion showing an image in a transitional sequence of the claimed design;

FIG. 7 is a front view of a cockpit display screen portion showing an image in a transitional sequence of the claimed design;

FIG. 8 is a front view of a cockpit display screen portion showing an image in a transitional sequence of the claimed design;

(Continued)

FIG. 9 is a front view of a cockpit display screen portion showing an image in a transitional sequence of the claimed design; and,

FIG. 10 is a front view of a cockpit display screen portion showing an image in a transitional sequence of the claimed design.

The appearance of the transitional graphical user interface sequentially transitions between the images shown in FIGS. 1 and 3 in a first embodiment, between the images shown in FIGS. 2 and 3 in a second embodiment, between the images shown in FIGS. 3 and 4 in a third embodiment, between the images shown in FIGS. 3 and 5 in a fourth embodiment, between the images shown in FIGS. 6 and 8 in a fifth embodiment, between the images shown in FIGS. 7 and 8 in a sixth embodiment, between the images shown in FIGS. 8 and 9 in a seventh embodiment, and between the images shown in FIGS. 8 and 10 in an eighth embodiment. The process or period in which one image transitions to another image forms no part of the claimed design.

The horizontally-aligned solid-lined rectangle illustrates the cockpit display screen portion.

The dot-dash broken lines illustrate a portion of a cockpit display environment and form no part of the claimed design. The broken-line subject matter within the horizontally-aligned solid-lined rectangle showing portions of a graphical user interface is included for the purpose of illustrating portions of the article of manufacture and form no part of the claimed design.
